UNITED STATES PATENT OFFICE.

WILLIAM TIPTON McCLOSKEY, OF WESTPORT, PENNSYLVANIA.

MILL-POND WASTE-WATER GATE.

SPECIFICATION forming part of Letters Patent No. 398,842, dated March 5, 1889.

Application filed June 5, 1888. Serial No. 276,162. (No model.)

To all whom it may concern:

Be it known that I, WILLIAM TIPTON McCLOSKEY, a citizen of the United States, residing at Westport, in the county of Clinton and 5 State of Pennsylvania, have invented certain new and useful Improvements in Mill-Pond Waste-Water Gates; and I do declare the following to be a full, clear, and exact description of the invention, such as will enable others skilled in the art to which it appertains 10 to make and use the same, reference being had to the accompanying drawings, and to the letters and figures of reference marked thereon, which form a part of this specification.

15 The special object of the invention is to make a waste-water gate for mill-ponds in order to keep the "head" of water at the same elevation whether the mill is running or standing still; also to adjust itself automatically in freshets, so as to discharge all surplus water.

Figure 1 of drawings is an elevation in perspective, showing the basin or pond separated from the chute leading to the mill drive-wheel 25 by my improved waste-water gate. Fig. 2 is a detail view showing gate closed in full lines and open in dotted lines.

30 A represents a beam with round ends, which have their bearings in the opposite vertical posts B B and connected by the arms *a* to the breast C, consisting of any desired number of planks or other material. The beam A has also rods or bars *a'*, extending over the chute D and carrying movable weights E near their

ends. The weights E are arranged on the 35 bars *a'* in such a position and at such leverage as to hold the breast C against the stops F F. As soon as the head of water begins to increase beyond that to which the gate has been set the increased pressure upon the 40 breast C causes the latter to augment its opening. For instance, I first move the weights to raise or lower the head of water toward or from the beam A, adjusting so as to raise the water in the pond two feet. Now, according 45 to my observation, one inch rise of water will cause the gate to open, turning, of course, in the arc of a circle having the beam A as its center. As the rise of water and consequent increase of pressure on the breast C continue 50 the gate will open more and more, so as to discharge the superfluous volume of water.

Having thus described all that is necessary to a full understanding of my invention, what I claim as new, and desire to protect by Letters 55 Patent, is—

A mill-pond waste-water gate consisting of the beam A, pivoted in posts B B, the breast C, connected by arms *a* with said beam, and the bars *a'*, attached to said beam, said bars 60 being provided with movable weights on their free ends, as and for the purpose set forth.

In testimony whereof I affix my signature in presence of two witnesses.

WILLIAM TIPTON McCLOSKEY.
